UNITED STATES PATENT OFFICE

167,838

VASE OR SIMILAR ARTICLE

Belle Kogan, New York, N. Y., assignor to The Red Wing Potteries, Inc., Red Wing, Minn.

Application May 22, 1952, Serial No. 19,829

Term of patent 7 years

(CL D29—28)

To all whom it may concern:

Be it known that I, Belle Kogan, a citizen of the United States of America, residing in New York City, county of New York, and State of New York, have invented a new, original, and ornamental Design for a Vase or Similar Article, of which the following is a specification, reference being had to the accompanying drawing, forming part thereof, wherein:

I claim:

The ornamental design for a vase or similar article, substantially as shown.

BELLE KOGAN.
